UNITED STATES PATENT OFFICE

FREDRIK W. HVOSLEF, OF KOHLER, WISCONSIN

DESIGN FOR A COMBINED RADIATOR AND HUMIDIFIER

Application filed February 4, 1932. Serial No. 42,727. Term of patent 14 years.

To all whom it may concern:

Be it known that I, FREDRIK W. HVOSLEF, a citizen of the United States, residing at Kohler, in the county of Sheboygan and State of Wisconsin, have invented a new, original, and ornamental Design for a Combined Radiator and Humidifier, of which the following is a specification, reference being had to the accompanying drawings, forming part thereof.

Figure 1 is a plan view, and Fig. 2 is a perspective view of the combined radiator and humidifier showing my new design.

I claim:

The ornamental design for a combined radiator and humidifier as shown.

FREDRIK W. HVOSLEF.
